UNITED STATES PATENT OFFICE.

JOSEPH BROOME, OF BAYONNE, NEW JERSEY, ASSIGNOR, BY DIRECT AND MESNE ASSIGNMENTS, TO CONCAVE AND CONVEX PRINTING COMPANY, A CORPORATION OF NEW YORK.

PRINTING-MACHINE.

No. 831,323.

Specification of Letters Patent.

Patented Sept. 18, 1906.

Application filed September 28, 1905. Serial No. 280,509.

To all whom it may concern:

Be it known that I, JOSEPH BROOME, a subject of the King of Great Britain, and a resident of Bayonne, in the county of Hudson and State of New Jersey, have invented certain new and useful Improvements in Printing-Machines, of which the following is a specification.

- This invention relates to means for printing and marking cylindrical objects, pencils, and the like. Its organization comprises a machine for printing and marking cylindrical objects, pencils, and the like with one or more colors.
- 15 It consists, essentially, of a rotating drum, to which are attached stationary and movable type-holders, a support adjacent to said drum mounted on flexible mediums, a conveyor to feed the objects to be printed on in proper position to the machine so as to be pinched between the drum and said support, and ink-rollers, with their appurtenances, to ink the type supported on the rotating drum.
- Figure 1 represents a side elevation of the invention. Fig. 2 shows an enlarged fragmentary cross-section of the drum, with its type-holders and appurtenances. Fig. 3 is an enlarged side view of a movable or slideable type-holder. Fig. 4 represents a top view of Fig. 3. Fig. 5 shows an enlarged side view of a stationary type-holder. Fig. 6 is a top view of Fig. 5. Fig. 7 represents a plan view of the invention. Fig. 8 is a partial section of Fig. 7 on the line xx . Fig. 9 shows a partial section of Fig. 7 on the line $x'x'$. Fig. 10 shows a front view of the invention. Fig. 11 is a plan view of the rotating drum, and Fig. 12 represents a rear view of the invention.
- 40 The machine shown in the drawings, which exemplifies the invention, comprises the rotating drum B, having the longitudinal openings b in its cylindrical surface on each side of the ribs b'. Cover-plates C are held in position on the cylindrical surface of the drum B by means of screws C' and contain the grooves C² and the curved flanges C³. On the ribs b' are fastened the stationary type-holders D by means of the screws d, and on each side of the holders D are located the movable type-holders E E'. The stationary type-holders D contain the pockets d' for the

type d², which latter are clamped in place by screws d³, and lugs d⁴ are located adjacent to said pockets. The holders E each have the pocket e for the type e', which latter are held in place by screws e². Longitudinal lugs e³ extend from the sides of the type-holders E and engage in the grooves C² of the cover-plates C. To the lower ends of the type-holders E are journaled the rollers e⁴. The type-holders E' are similar in construction to the holders E and have journaled thereto the rollers E⁴. The drum B has the fixed head B', and the removable head B², the latter being secured in place by the bolts B³. Journal-sleeves B⁴ B⁵ extend from the said heads, which are carried and rotate on the shaft F. A pulley F⁴ is carried on the sleeve B⁵, and the shaft F is held stationary in the supports F' by set-screws F², which prevent the shaft turning.

On the shaft F is supported the grooved drum F³ with the grooves f f', in which are engaged the rollers e⁴ and E⁴ of the movable type-holders. On the shaft F are fastened the spur-gears G, that mesh with the pinions G', carried on shaft G², supported in the journal-boxes G³. On the ends of the shaft G² are fastened the cranks H, to which are journaled the links H', the latter being connected with the arms i of the bell-cranks I. Extending from the frame A are the brackets A', which support the journal-brackets I' for the shaft I². The arms i² of the bell-cranks I enter the roll-holders J and have each a slot J', through which passes a pin J², secured in the said holders. The latter have the forked ends J³ for the ends of the roller-shaft K, which carries the rollers K', that roll on the flanges B⁶ of the drum and the inking-rollers K² K³ K⁴. A spring J⁴ bears between outer end of each of the holders J and the collar i² of the arm i² of each bell-crank I.

Adjacent to the shaft G² is journaled the shaft L, which carries the bevel-gears L', that mesh with the bevel-gears L². Bearings M and M' extend from the frame A to support the said gears in proper position. The bevel-gears L² have secured thereto the spindles N, that carry the revolving disks N'. Attached to the frame A are the brackets O, that carry the guides O'.

Extending from the frame A is the hollow

2
guide-box P, in which fits the movable support Q. The box P has the internally-threaded sleeves P', into which are screwed the guides P², that have the hexagonal ends P³. The movable support Q carries the removable bearing-plate Q' with the facing Q², which latter is generally of rubber and corrugated. Spindles Q³ are fastened in bosses Q⁴ in the support Q and extend through the guides P². Springs Q⁵ bear between the bosses Q⁴ and guides P², and nuts Q⁶ with flanges Q⁷ are secured on the ends of the spindles Q³.

Supporting-fingers R are carried on the shaft R', which is supported in the sides of the movable support Q, and counterweights R² extend from the said shaft on the outside of the box P, the said box having suitable enlarged openings for the shaft R'. Extending from the box P are the brackets S, to which are bolted the bearings S' on one end. On the outer ends of the brackets are supported the adjustable bearings S². The bearings S' carry the shaft S³, on which is fastened the drying sprocket-wheel S⁴, and the adjustable bearings S² carry the shaft S⁵ with the drum S⁶. Sprocket-chains T are carried on the wheels S⁴ and drum S⁶. From the said chains extend the pins t, which carry the buckets t', that constitute a conveyer. Over the conveyer is supported a hopper T' by means of brackets T², that are bolted to the hopper and the brackets S. On the shaft S³ is supported the notched wheel V, that meshes with the lugs V' of the wheel V². There are four of the lugs V'—that is, one for each set of type-holders—and the notches on the wheel V² are such that the conveyer is moved the distance of one bucket each time a lug V engages with a notch of the wheel V². On the bearing B⁴ is supported an eccentric B', which carries an arm B⁸, the bent end of which engages with a ratchet-wheel B⁹ on the end of the shaft L.

45. To operate the invention, the objects, like pencils, are placed in the hopper T', from which they are taken by the conveyer with the buckets t' and conveyed to the bearing-plate Q' of the movable support Q, on which they are held in proper position parallel to the axis of the drum B by means of the fingers R. When the said drum revolves, the pencils are pinched between the bearing-plate Q' and the curved flanges C³, extending from the cover-plates C. Upon the further movement of the drum the pencils are turned and rolled down the said bearing-plate, while the type in the type-holders are printing on their surfaces. The fingers R are pushed out of the way as the pencil rolls down the bearing-plate, and the pencils after having been printed roll off of the said support. While the pencil is being printed the movable type-holders E and E' are held next adjacent to

the stationary holder D by virtue of the 65 grooves f and f' in the groove-drum F being parallel and close to each other. As the drum B approaches a position one hundred and eighty degrees from the position where the printing has been performed the grooves 70 f and f' have diverged and again become parallel, but at a greater distance apart, thereby carrying the rollers e⁴ and E² apart, and consequently sliding or moving the movable type-holders so as to bring them out of line 75 and distant from each other. When the type-holders are out of line, the type in the stationary and movable type-holders can be inked independently of each other without danger of an ink-roller intended for the type 80 in one holder inking the type of one of the other holders. Also when the type-holders are out of line the ink-rollers through their connections have rolled from the disks N to the type in the type-holders, inking them 85 with the necessary ink. The guides O' support the rollers K when the ink-rollers leave the disks N' and before they ink the type in the type-holders. By these movements of the type-holders different colors of ink can be 90 used on the different disks and ink-rollers.

Four sets of type-holders with type are shown and disks for three different colors. It is evident that more or less sets of type-holders could be located in the rotating drum and 95 that a less or greater number of the type-holders could be made movable. While the drum is rotating the disks N' are being turned by virtue of the hook end of the arm B⁸ engaging with the ratchet-wheel L'.
100

Having described my invention, I claim—

1. In a printing-machine the combination of a drum, means to rotate the drum, a movable type-holder on the cylindrical surface of the drum, type secured in the holder, means 105 to move the movable type-holder in directions parallel to the longitudinal axis of the drum, and a support adjacent to the drum for objects to be printed upon.

2. In a printing-machine the combination 110 of a drum, means to rotate the drum, a stationary type-holder on the drum, a movable type-holder on the cylindrical surface of the drum, means to move the movable type-holder on the surface of the drum, type secured in the type-holders, and a support adjacent to the drum for objects to be printed upon.
115

3. In a printing-machine the combination 120 of a drum, means to rotate the drum, a stationary type-holder on the drum, a movable type-holder on the cylindrical surface of the drum, means to move the movable type-holder on the surface of the drum, type secured in the type-holders, a support adjacent to the drum for objects to be printed upon, and a flexible medium carrying the support.
125

4. In a printing-machine the combination

- of a drum, stationary and movable type-holders on the drum, means to rotate the drum, a support adjacent to the drum, a cover-plate on the drum, and a flexible medium to carry the said support.
5. In a printing-machine the combination of a drum, stationary and movable type-holders on the drum, type secured in the holders, means to rotate the drum, a support adjacent to the drum, a flexible medium carrying the support, fingers on the support, to hold an object to be printed on in proper position.
6. In a printing-machine the combination of a drum, a stationary and movable type-holder on the drum, means to rotate the drum, a support adjacent to the drum, a flexible medium to carry the said support, movable fingers carried on the support to hold an object in proper position before being printed on, type in the type-holders, and means to ink the type.
7. In a printing-machine the combination of a drum, a stationary type-holder securely fastened to the drum, movable type-holders on the drum, means to move the said movable holders, movable fingers carried on the support to hold an object in proper position before being printed on, type in the holders, and means to ink the type in each holder.
8. In a printing-machine the combination of a drum, a stationary type-holder securely fastened to the drum, movable type-holders guided in openings parallel to the stationary type-holder, a stationary shaft supporting the drum, a grooved drum secured to the shaft, the said grooves engaging the movable type-holders, an ink-disk for each type-holder supported in the machine, means to rotate the disks, a roller-shaft arranged to swing from over the disks to the type in the type-holders, and an ink-roller on the roller-shaft, for each disk.
9. In a printing-machine the combination of a rotating drum, stationary and movable type-holders supported on the drum, type in the type-holders, means to move the movable type-holders, means to ink the type in the type-holders after they have been moved from each other, a movable support adjacent to the drum, flexible means to hold the movable support in position, curved flanges rotating with the drum to pinch objects against the movable support, fingers extending from the support to hold an object in proper position.
10. In a printing-machine the combination of a rotating drum, stationary and movable type-holders supported on the drum, type in the said holders, means to move the movable type-holders, means to ink the type in the holders, a support adjacent to the drum, a spindle extending from the support, a box to guide the movable support, guides for the spindle extending through the said box, a spring-bearing between the said guide and movable support, and means to vary the tension of said spring.
11. In a printing-machine the combination of a rotating drum, stationary and movable type-holders supported on the drum, type in said holders, means to move the movable type-holders, means to ink the type in the holders, a support adjacent to the drum, a spindle extending from the support, a box to guide the movable support, threaded guides for the spindle extending through the said box, a spring-bearing between the said guide and the movable support, a hexagonal end on the guide, a nut with a flange on the spindle bearing against said hexagonal end.
12. In a printing-machine the combination of a drum, means to rotate the drum, a stationary type-holder on the drum, a movable type-holder on the surface of the drum, means to move the latter type-holder on the surface of the drum, a support adjacent to the drum, a flexible medium carrying the support, fingers on the support to hold an object to be printed in proper position, and flanges moving with the drum to pinch the object to be printed against the movable support.
13. In a printing-machine the combination of a drum, means to rotate the drum, a support adjacent to the drum, a flexible medium carrying the support, fingers on the support to hold an object to be printed in proper position, flanges moving with the drum to pinch the object to be printed, a conveyer to feed the objects to be printed to the movable support, a stationary type-holder on the drum, movable type-holders on the surface of the drum, means to move the movable type-holders on the surface of the drum.
14. In a printing-machine the combination of a drum, means to rotate the drum, a support adjacent to the drum, a flexible medium carrying the support, cover-plates over openings in the cylindrical surface of the drum, a rib in the said opening, a type-holder secured to said rib, movable type-holders arranged to move in the opening between the said rib and the edges of the said cover-plates, a grooved drum supported on a stationary shaft extending through the axis of the drum, rollers journaled on the movable type-holders engaged with the grooves of the grooved drum.
15. In a printing-machine the combination of a frame, a rotating drum thereon, a fixed head at one end of the drum, a removable head at the other end of the drum, journal-sleeves extending from said heads, journal-bearings in the frame for said sleeves, a shaft extending through the axis of the sleeves, supports on the frame outside of said bear-

ings to hold and clamp the shaft in position, a grooved drum supported on the shaft inside of the rotating drum, type-holders on the rotating drum, means to print objects with said 5 type, means to ink said type, and means to rotate the drum.

16. In a printing-machine the combination of a drum, a stationary and movable type-holder on the drum, type secured in the 10 holders, means to rotate the drum, a support adjacent to the drum, a flexible medium carrying the support, means to pinch the object to be printed upon between the support and drum, type-holders moving with the drum, a 15 conveyer adjacent to the rotating drum, means to move the conveyer for each object that is printed by the type of the drum.

17. In a printing-machine the combina-

tion of a drum, means to rotate the drum, a support adjacent to the drum, a flexible medium carrying the support, means to pinch the object to be printed upon between the support and drum, type-holders moving with the drum, a conveyer adjacent to the rotating drum; means to move the conveyer, a 20 driving-shaft for the conveyer, a notched wheel on the said driving-shaft, a wheel having lugs rotating with the drum, said lugs meshing with the said notched wheel.

Signed at New York, in the county of New 30 York and State of New York, this 27th day of September, A. D. 1905.

JOSEPH BROOME.
